UNITED STATES PATENT OFFICE.

WILLIAM F. CUMMINGS, OF PLATTSBURG, NEW YORK.

WINDOW-SCREEN.

No. 799,719.

Specification of Letters Patent.

Patented Sept. 19, 1905.

Application filed December 12, 1904. Serial No. 236,553.

To all whom it may concern:

Be it known that I, WILLIAM F. CUMMINGS, a citizen of the United States, residing at Plattsburg, in the county of Clinton 5 and State of New York, have invented certain new and useful Improvements in Window-Screens; and I do hereby declare the following to be a full, clear, and exact description of the invention, such as will enable others skilled in the art to which it appertains to 10 make and use the same.

This invention relates to window-screens for use in preventing flies from entering dwelling-houses; and it consists in the novel 15 construction and combination of the parts hereinafter fully described and claimed.

In the drawings, Figure 1 is a front view of the screen applied to a window with a portion of its casing broken away. Fig. 2 is a 20 section through the screen, taken on the line *x x* in Fig. 1. The remaining figures are drawn to a larger scale. Fig. 3 is a front view, Fig. 4 is a plan view, and Fig. 5 is a rear view, of a portion of the top bar of the screen. 25 Fig. 6 is a cross-section taken on the line *y y* in Fig. 5. Fig. 7 is a front view of a portion of the roller. Fig. 8 is a cross-section taken on the line *z z* in Fig. 7. Fig. 9 is a side view of one of the roller-brackets, showing the 30 ratchet-wheel and pawl.

A is a portion of a window-frame of any approved construction, and *b* is the window-sill.

B is a portion of the lower window-sash, 35 which slides in the window-frame in the usual manner.

C is a roller which is journaled in suitable bearings at the lower part of the window-frame inside the window and close above the 40 window-sill. This roller is a spring-actuated roller of any approved construction, such as used for window-curtains, and it may be made in one piece or in extensible sections. 45 *D* is a rectangular shaft which projects at one end of the roller and which engages with a disk *d*, which is journaled in a bearing-plate *d'*, secured in a recess in one of the brackets *E* at the side of the window-frame. The other end portion of the shaft *D* is 50 operatively connected with the spring of the roller.

The brackets *E* are secured to the faces of the sash-guides or weight-boxes of the frame, so that spaces *a'* are formed between the brackets and the side portions of the frame 55 to give access to the ends of the roller-spline.

F is a ratchet-toothed wheel on the disk *d*. This wheel is preferably arranged next to the end of the roller, and *f* is a pawl which is pivoted to the bracket and which engages with 60 the said wheel. This pawl is held in engagement with the wheel by a spring *f'*; but this spring may be omitted, if desired. The tension of the roller-spring is adjusted by means of an ordinary key or wrench applied to the 65 projecting rectangular end portion of the shaft *D*.

G is a wire screen or any other screen fabric which will keep out flies. This screen is wound upon and secured at its lower edge to 70 the roller *C*.

H is a bar at the top edge of the screen *G*. The top edge of the screen is inclosed between a channel-shaped metallic strip *r*, and this strip and the edge of the screen are nailed or 75 otherwise secured to the said bar.

I represents two tabs of flexible material secured to the said bar and affording a means of securing the upper edge of the screen to the window-sash. The lower part of the 80 window-sash has the tabs connected to it by pins *i*.

In order that the screen may be readily applied to windows of different size, the screen, its roller, and the top bar are all preferably made 85 in sections, so that they may be extended. The main section of the roller *C* is provided with a series of longitudinal projections *J*, and the extensible section *C'* of the roller is provided with longitudinal projections *j*, which are 90 slidable between the said projections *J*. Each section of the roller is preferably provided with four projections, and the diameter of the roller at the projections *j* is preferably a little less than the diameter of the main 95 section of the roller, so that the overlapping portions of the sections of the screen may slide in contact with each other without too much friction. *G'* is the extensible section of the wire screen, which is secured to the 100 extensible section *C'* of the roller.

The bar *H* is provided with an extensible section *H'*, to which the section *G'* of the screen is secured. The main portion *H* of the bar is provided with a longitudinal projection at its upper edge, and the main part *G* of the screen is secured along the upper edge of the bar *H* and its projection *h*. The extensible section *H'* of the bar is provided with a projection *h'* at its lower edge, which 105 slides under the projection *h*. The lower edge of the section *H'* and its projection *h'* 110

are cut away to form a space k , in which the upper edge of the screen-section G' is secured, so that the said screen-section may slide freely behind the main portion of the screen.

5 The main portion of the bar is provided with a back piece N , which is rigidly secured to it and which is provided with a slot n at one end. The section H' of the bar is provided with a back piece N' , which is rigidly 10 secured to it and which is provided with a projecting tongue which is slidable in the slot n . The tongue n' is arranged at the middle part of the end of the back piece, and it comes over the crack or space between the 15 projections h and h' . The back pieces stiffen the bar and enable it to be extended in a satisfactory manner.

The side edges of the screen are slidable in grooved guides P , which are secured to the 20 brackets E and arranged against the window-frame. S is a casing secured to the said brackets in front of the roller G .

In order to prevent flies from passing under the roller, the casing is provided with a guide 25 s , and t is a packing-piece which is slidable in the said guide. This packing-piece is preferably arranged at a tangent to the rolled screen and is provided with a beveled edge t' , which presses against the wire screen. 30 Springs s' may be applied behind the packing-piece to hold it in contact with the rolled screen. The screen pushes back the packing-piece with very little friction as it winds upon the roller, because of the inclination of 35 the said packing-piece with respect to the roller.

T is a stiffening-ring of thin metal which is secured over the projections of the roller-sections. This ring is secured to one section, so 40 that the projections of the other section may slide freely.

The screen fabric is nailed to the roller-section C on each side of the ring T and overlaps the said ring. This ring is formed of 45 very thin sheet metal, and it does not materially increase the diameter of the roller-section.

What I claim is—

1. In a window-screen, the combination, with a bar-section H having a projection h 50 at its upper edge, of a bar-section H' having a projection h' at its lower edge which slides under the projection h , a screen-section secured to the lower part of the bar-section H' and its projection h' , and a screen-section secured to the upper part of the bar-section H 55 and its projection h and overlapping the aforesaid screen-section.

2. In a window-screen, the combination, with a bar-section H having a projection h 60 at its upper edge, of a bar-section H' having a projection h' at its lower edge which slides under the said projection h , the said projection h' and the lower part of the bar-section H' being of less width than the bar-section H 65 and its projection h , and the backs of the said parts being arranged flush with each other, a screen-section secured to the lower part of the bar-section H' and its projection h' , and a screen-section secured to the upper part of 70 the bar-section H and its projection h and overlapping the aforesaid screen-section.

3. In a window-screen, the combination, with a bar-section H having a projection h 75 at its upper edge, of a bar-section H' having a projection h' at its lower edge which slides under the projection h , a bar-section N secured to the back of the bar-section H and having a groove n in the middle part of one end portion, a bar-section N' secured to the 80 back of the bar-section H' and having a tongue n' which slides in the groove n over the adjacent portions of the said projections h and h' , a screen-section secured to the lower 85 part of the bar-section H' and its projection h' , and a screen-section secured to the upper part of the bar-section H and its projection h and overlapping the aforesaid screen-section.

In testimony whereof I have affixed my signature in the presence of two witnesses. 90

WILLIAM F. CUMMINGS.
